UNITED STATES PATENT OFFICE

JAMES MORKOVSKI, OF CANTON, ILLINOIS, ASSIGNOR TO INTERNATIONAL HARVESTER COMPANY, A CORPORATION OF NEW JERSEY

DISK FURROW OPENER

Application filed September 24, 1931. Serial No. 564,781.

This invention relates to improvements in depth gaging devices for tillage disks, particularly those such as are employed on grain drills.

More specifically, the invention relates to improved means for adjusting the position of the gaging means.

In the use of tillage disks for certain purposes in certain types of soil, it has been found desirable to attach a gage band to the disks concentric with respect thereto to maintain the working depth of the disk at a predetermined level. It has also been found desirable to provide means for altering the radial position of the gage band. The U. S. patent to Cady, #1,790,089, discloses and claims a tillage disk having an adjustable gage band.

The principal object of this invention is to provide improved means for altering the radial position of a gage band for tillage disks. Other objects and the means by which they are accomplished will be apparent from the detailed description to follow.

In the drawings:

Figure 1 is a perspective view of a tillage disk embodying the invention;

Figure 2 is a perspective view of the same structure shown in Figure 1 with the gage band in a different position of adjustment;

Figure 3 is an elevation of a modified form of the invention;

Figure 4 is an elevation of the same construction shown in Figure 3 with the gage band in a different position; and

Figure 5 is a section taken on the line 5—5 of Figure 3.

The invention is illustrated as embodied in an organization as shown in Figures 1 and 2, comprising a furrow opening disk 10 having a hub 11 rigidly secured thereto. The hub has a central axial opening by which means the disk is mounted upon a seed drill or other implement on which it is to be used. A plurality of circumferentially spaced bracket members 12 are secured to the face of the disk by bolts 13 extending through the members and through the disk. The bolts 13 are evenly spaced circumferentially and equally spaced from the center of the disk. Said bolts form pivot axes for the members 12.

Each bracket member 12 has a head portion 14 which extends at right angles to the surface of the disk to form a support for the gage band 15. The outer surface of the head portion 14 is curved eccentrically with respect to the pivot axis of the member 12 on the bolt 13. The head portion 14 is provided with an upwardly extending flange 16 spaced from the disk 10 a distance equal to the width of the band 15 whereby said head portion engages the band internally and laterally to hold it in position against the disk.

Each member 12 is also provided with a lever arm 17 extending inwardly toward the center of the disk. An annular actuating member 18 is mounted concentrically with respect to the hub 11 around the periphery thereof, the outer edge of the hub forming a guide contacting with the inner edge of said member. The member 18 is provided with pairs of spaced regularly extending lugs 19. Each pair of said lugs is positioned to embrace one of the levers 17. The lugs are of a sufficient distance apart to allow rotative movement of the member 18 without binding the lever 17 against the lugs. At one location around its periphery the member is provided with an extension 20 in which a circumferentially extending slot 21 is formed. A bolt 22 extends through said slot and through the disk 10. The gage band 15 is provided with a plurality of spaced holes 23 adjacent one end thereof. Said holes provide means for attaching the ends of the band together in a plurality of extended positions by means of a bolt 24 extending through an opening in the other end of the band.

Figure 2 shows the gage band in contracted position. This position permits a maximum depth of penetration of the disk 10. To move the gage band 15 radially outwardly the bolt 24 is removed and positioned in one of the openings 23, which will give the band an increased diameter. The bolt 22 is then loosened and the member 18 is rotated in a direction to move the levers 17 in such a direction that the head portion 14 of each member 12 will move radially outwardly. The cam faces on the head portion 14 provide for and form even contact at any location of the mem-

- bers 12. If the bolts 13 are securely tightened it may be necessary to loosen them before operating the actuating member 18. It will be understood that as the member 18 is rotated, each of the members 12 is moved an equal angular distance whereby the head portions will move outwardly an equally radial distance to engage the band and hold it concentrically with respect to the center of the disk.
- 10 When the desired adjustment has been secured, the bolt 22 is securely tightened. The bolts 13 may also be tightened if it is so desired. In providing this actuating means for the band bracket members, the band may be quickly and accurately adjusted circumferentially and held in concentric position on the disk.

Figures 3, 4, and 5 show a modified form of actuating means for simultaneously moving the band supporting bracket members. The disk 25 is provided with a plurality of spaced holes around the center for attachment to a hub member, such as shown in Figures 1 and 2. The bracket members 26 are secured at circumferentially spaced positions on the disk by bolts 27 equally spaced around the disk and on the same radii. The members 26 are provided with head portions 28 having a cam-like engaging band engaging face substantially perpendicular to the surface of the disk. Outward extensions 29 provide means for engaging the outer edge of the gage band 30. The gage band is formed as an extensible element by being provided with a plurality of openings 31 adjacent one end and a removable bolt 32 extending through one of said openings and through an opening in the other end of the band. Each of the members 26 is provided with an apertured ear 33 extending radially inwardly with respect to the bolt 27, as shown in the contracted position in Figure 3. Each of the members 26 is also provided with a second apertured extension 34. As best shown in Figure 5, the extension 33 lies close to the disk 25. The extension 34 is spaced outwardly a considerable distance therefrom for a purpose to be hereinafter described. A link 35, having parallel end extensions arranged at an angle with respect to the direction of extension of the link, connects each member 26 with the adjacent member. One end of the link is connected to the center of the extensions 33 adjacent the disk. 50 The link extends upwardly from said extension and the other end pivotally connects the extension 34 on the adjacent bracket member. As will be understood by inspecting Figure 3, there are four of the links 35 connecting each of the lower extensions 33 with one of the extensions 34 on the adjacent bracket member. The extensions 33 and 34 are a sufficient axial distance apart to provide for rotative movement of the bracket members 26, 55 as will be hereinafter described, without en-

gagement of the two links which cross one another.

Figure 4 illustrates this modification of the invention with the gage band in extended position. To obtain such an adjustment the band 30 is extended and the bolts 27 are loosened to permit rotation of the members 26. As the members are all linked together, as above described, they are simultaneously rotated an equally angular distance, whereby the band is engaged and held in concentric relation with respect to the disk 25. When the desired adjustment has been accomplished, the bolts 27 are tightened to maintain the members 26 in position.

It is to be understood that applicant has shown and described only certain preferred embodiments of his depth gage for tillage disks and that he claims as his invention all modifications falling within the scope of the appended claims.

What is claimed is:

1. The combination with a tillage disk of a plurality of bracket members pivotally mounted on a face of the disk at circumferentially spaced points around its center and formed with angular extensions perpendicular to the disk face, a circular extensible gage band seated on said angular extensions, and means to simultaneously move the bracket members equally radial distances.

2. The combination with a tillage disk of a plurality of bracket members mounted on a face of the disk at circumferentially spaced points around its center and formed with angular extensions perpendicular to the disk face, a circular extensible gage band seated on said angular extensions, and means to simultaneously move the bracket members equally angular distances.

3. The combination with a tillage disk of a plurality of bracket members supported on a face of the disk at circumferentially spaced points around its center, said members each having a portion mounted on the disk for angular adjustment and a head portion perpendicular to the disk face and curved on an arc eccentric to the axis of angular adjustment, an extensible band seated on the head portions of said members, and means to simultaneously angularly adjust said members radially of the disk.

4. The combination with a tillage disk of a plurality of bracket members supported on a face of the disk at circumferentially spaced points around its center, said members each having a portion mounted on the disk for adjustment radially and a head portion perpendicular to the disk face and curved on an arc eccentric to the axis of angular adjustment, an extensible band seated on the head portions of said members, and means to simultaneously adjust said members.

5. A tillage disk depth gage comprising in combination with a disk an annular exten-

sible band, a plurality of spacing members rotatably secured to the disk on fixed axes, said members being shaped to engage and positioned to hold said band against the disk
5 concentric with respect thereto, the engaging surfaces on the members being eccentric with respect to the axes of the members whereby rotation of the members alters the radius of their engaging surfaces, and means
10 to simultaneously rotate each of said members an equal angular distance.

6. A device as set forth in claim 3 in which each of the spacing members is provided with an inward extension and in which an
15 actuating member mounted concentrically with respect to the disk is operable to engage and simultaneously rotate each of the spacing members an equal angular distance.

7. A device as set forth in claim 3, in
20 which each of the spacing members is connected by a link to one of the other spacing members, said links being so connected that when one of the members is rotated each of the other members is rotated an equal angular
25 distance.

In testimony whereof I affix my signature.
JAMES MORKOVSKI.
